UNITED STATES PATENT OFFICE.

GEORGE HARVEY ELMER, OF PLEASANT VALLEY, OREGON.

POTATO-PLANTER.

SPECIFICATION forming part of Letters Patent No. 744,181, dated November 17, 1903.

Application filed July 27, 1903. Serial No. 167,200. (No model.)

To all whom it may concern:

Be it known that I, GEORGE HARVEY ELMER, a citizen of the United States, residing at Pleasant Valley, in the county of Baker and State of Oregon, have invented a new and useful Potato-Planter, of which the following is a specification.

This invention relates to machines for planting potatoes; and it has for its object to provide a device of this class which shall possess superior advantages in point of simplicity, durability, and general efficiency.

Another object of this invention is to so construct my improved potato-planter that it may be mounted for operation upon the frame of a check-row corn-planter of ordinary construction, thereby effecting a great saving in the carrying-trucks.

A further object of my invention is to so construct my improved potato-planting device that it may be operated continuously as a drill or intermittently as by the check-rowing mechanism of the planter-frame upon which it is mounted.

With these and other ends in view my invention consists in the improved construction, arrangement, and combination of parts, which will be hereinafter fully described, and particularly pointed out in the claims.

My improved potato-planting device may, as aforesaid, be mounted upon the frame of an ordinary check-row corn-planter, while at the same time it may obviously be provided with a specially-constructed carrying-frame.

In the accompanying drawings I have shown my invention as mounted upon the frame of an ordinary corn-planter, and I desire it to be understood that I do not limit myself to the precise structural details, but reserve the right to any changes of shape, proportions, or general assemblage of parts which may be resorted to within the scope of my invention.

In said drawings, Figure 1 is a perspective view of my improved potato-planter, showing the same applied to the frame of a check-row planter. Fig. 2 is a vertical sectional view of the potato-planter detached from the check-rower frame. Fig. 3 is a vertical sectional view taken on the line 3-3 in Fig. 2. Fig. 4 is a horizontal sectional view taken on the line 4-4 in Figs. 2 and 3. Fig. 5 is a perspective detail view showing a portion of

one of the disks with one of the pickers and doffers.

Corresponding parts in the several figures are indicated by similar numerals of reference.

The planter-frame is composed of the wheel-frame 1 and the runner-frame 2, which are suitably connected, said wheel-frame being supported upon the axle 3, carrying the traction and covering wheels 4, while the runner-frame includes in its construction the runners or furrow-openers 5, the check-row mechanism 6, the connecting-bar 7, and the tongue 8.

The main frame of my improved machine supports a base-board 9, provided at its rear corners with recesses 10 for the passage of the rims of the transporting-wheels. The base 9 is provided at the ends thereof with uprights 11, in the upper ends of which is journaled a shaft 12, which may be provided at the ends thereof with nuts 13 in order to prevent lateral displacement. In the example shown in the drawings the uprights are simply constructed of suitably-braced L-shaped brackets, which are mounted upon the base and the upward-extending arms of which are perforated for the reception of the screw-threaded ends of the shaft 12, which is retained in said openings by the nuts 13. I do not limit myself to this construction; but I have described and illustrated the same on account of its inexpensiveness, an important object of my invention being to furnish a machine which will effectively accomplish the work for which it is intended at a very moderate expense.

Uprights 14 rising from the base 9 support a hopper 15, the central part of the bottom of which is preferably of inverted-V shape, as shown at 16, whereby the hopper will be divided into two separate compartments having contracted bottoms, from which auxiliary hoppers 17 extend downwardly and outwardly, as shown, the lower edges of said auxiliary hoppers being preferably segmental and concentric with the axis of the shaft 12. The auxiliary hoppers 17 are composed of the funnels 18 and inner side extension-plates 19, having flanges 20. The outer walls of the auxiliary hoppers are composed of disks 21, secured upon the ends of a tube 12^a, which

is mounted revolvably upon the shaft 12, and which said disks will be more clearly described. Suitably secured to the front side of the funnels of the auxiliary hoppers are 5 the dropping-tubes 22, which are simply composed of flanged plates, the outer sides of said dropping-tubes being also formed by the revolvable disks 21. The latter, which are dished or convexo-concave, in the manner of 10 ordinary plow or cultivator disks, are mounted securely upon the tube 12^a by means of set-screws extending through the hubs of said disks and engaging the said tube. These disks, while they are utilized to close or to 15 form the outer walls of the auxiliary hoppers and the dropping-tubes, are not placed absolutely tightly against the flanges constituting the front and rear walls of said auxiliary hoppers and dropping-tubes, but a sufficient 20 distance from said flanges to admit of the passage of the planting devices, which will be now more fully described.

Suitably secured upon the inner side of each of the revolvable disks 21 is a plurality 25 of equidistantly-spaced shanks 24, which in practice may be about one-half inch in length and which carry laterally-extending prongs 25, forming pickers, which may be described as lying parallel to the peripheries of the 30 disks. These pickers, the points of which extend forwardly when at the upper limit of the movement of the disk to which they are attached, are disposed at a distance from the edge of said disk to permit them to pass with- 35 in the lower ends of the auxiliary hoppers when the machine is in operation. In suitable proximity to each of the pickers is pivotally mounted a lever 26, one end of which has a raised portion 27, forming a doffer 40 which engages against the under side of the picker, the opposite end of said lever being provided with a counterweight 28, the movement of which is limited by means of a stud 29, suitably projecting from the inner face of 45 the disk. Secured to the front side of the hopper directly above the dropping-tubes 22 are trip-bars 30, extending transversely across said tubes and adapted to engage the counterweights of the doffing-levers for the purpose 50 of actuating the latter at the point of discharge.

Suitably mounted upon the inner sides of the ends of the main hopper are vertically-movable slides 34^a, which extend into the 55 auxiliary hoppers and by means of which the supply of potatoes from the main into the auxiliary hoppers may be accurately regulated in order to prevent said auxiliary hoppers from being choked. The operation of 60 this part of my invention will be readily understood from the foregoing description, taken in connection with the accompanying drawings.

Motion may be imparted to the tube 12^a by 65 means of a chain 31, connecting the sprocket-wheel 32 upon said tube with a sprocket 33 upon the axle of the main frame of the ma-

chine, the speed of the dropping mechanism being regulated by the relative sizes of the said sprocket-wheels, whereby the potatoes 70 may be dropped at any desired distance apart. When the machine progresses over the field and the tube 12^a revolves, the disks 21, which constitute the outer sides or walls of the auxiliary hoppers and of the dropping-tubes, will 75 be rotated in the direction indicated by arrows. As the pickers pass through the lower portions of the auxiliary hoppers, which, as stated, are preferably segmental in shape in order that no obstruction may be presented 80 to the rotation of the disks, the pickers upon said disks will unfailingly engage the potatoes or spuds contained in the auxiliary hoppers, the doffers being by the engaging action of the pickers forced into engagement 85 with the shanks of the latter, while the potatoes adhere to the pickers with a sufficient degree of firmness to enable them to be carried to the point of discharge. When the latter is reached, or when, in other words, 90 the pickers are disposed directly above the upper ends of the dropping-tubes, the weighted ends of the doffing-levers will be engaged by the drop-bars 30, thus tripping the doffers and depositing the potatoes in the dropping-tubes. As the rotation of the disks progresses, the weighted ends of the doffers will 95 restore the latter to their proper position in engagement with the shanks of the pickers, so that the action of the potatoes engaging 100 said pickers shall not be altogether relied upon to force the said doffers into position. It is obvious that the movement of the doffing-levers is limited by the studs 29, which engage the weighted ends of said levers. It 105 is also evident that the weighted ends of the doffing-levers will project beyond the peripheries of the disks, the intermediate flat portions of the doffing-levers being of such a thickness that they may pass through the 110 spaces between the edges of the disks and the adjacent walls of the auxiliary hoppers and the dropping-tubes, while said spaces would be 115 too narrow to admit the weighted ends of the lever.

The rear side of the hopper 15 is provided with bearings for a rock-shaft 36, having a downwardly-extending arm 37, which lies in the path of a trigger 38, secured upon the revolvable tube 12^a. A spring 39 is suitably disposed to rotate the rock-shaft 36 in the direction opposite to that in which it is actuated by the trigger 38. The ends of the rock-shaft 36 are provided with arms 40, extending through openings 41 in the rear side wall of 125 the hopper, and the said arms 40 are provided with agitators 41', which serve to agitate the contents of the main and auxiliary hoppers, so that choking of the feed will be prevented.

When my improved potato-planting device, as in the drawings hereto annexed, is mounted upon the frame of a check-row corn-planter, the seedboxes and valves of the latter are re-

moved, and the upper ends of the runner-tubes may be provided with funnels 42, which are connected with the lower ends of the dropping-tubes 22 by means of a conducting-tube 43, which may be secured by means of brackets to the front corners of the base of the potato-planting attachment.

If it is desired to plant the potatoes in hills or check-rows, this may be readily accomplished by the use of tappet-wires of ordinary construction, the latter being stretched across the field, so as to coöperate with the check-row mechanism of the planter, from which motion may then be imparted to the tubular shaft 12^a by any well-known mechanism or mode of transmission. Similarly, whenever desired, the potato-planting mechanism may be removed from the frame of the corn-planter, and the latter may then, by restoring the parts thereof which have been temporarily removed, be utilized for the purpose of planting corn.

As will be seen from the foregoing, my improved potato-planting device is simple in construction, effective in operation, and may be supplied at a very small expense. Considering the simplicity of its construction, it will be found that my improved machine is of very large capacity and that the work performed thereby is in every respect perfect.

Having thus described my invention, I claim—

1. In a potato-planter, a hopper, auxiliary hoppers connected therewith, and having bevel-edged extension-plates, dropping-tubes comprising flanged plates connected with the front sides of the auxiliary hoppers, and revolute disks constituting the outer sides of said auxiliary hoppers and dropping-tubes.

2. In a potato-planter, a hopper, auxiliary hoppers connected therewith, and having bevel-edged extension-plates, dropping-tubes comprising flanged plates connected with the front sides of said auxiliary hoppers, revolute disks constituting the outer walls of said auxiliary hoppers and dropping-tubes, pickers mounted upon the inner sides of said disks, doffing-levers associated with said pickers, and trip-bars extending transversely across the dropping-tubes.

3. In a potato-planter, a hopper, auxiliary hoppers connected therewith and having bevel-edged extension-plates, revolute disks constituting the outer sides of said auxiliary hoppers, pickers and doffers associated with said revolute disks and gage-slides mounted upon the inner sides of the end pieces of the hopper.

4. In a potato-planter, a hopper, a central inverted-V-shaped partition therein converting said hopper into two compartments, auxiliary hoppers connected with said compart-

ments and having bevel-edged extension-plates, gage-slides mounted upon the inner ends of said hopper and extending into the 65 said auxiliary hoppers, revolute disks constituting the outer walls of said auxiliary hoppers, pickers and doffers associated with said revolute disks, dropping-tubes, and tripping means extending across the latter to 70 actuate the doffers.

5. In a potato-planter, a hopper, auxiliary hoppers connected therewith, and having bevel-edged extension-plates, dropping-tubes comprising flanged plates connected with said auxiliary hoppers, a suitably-supported revolute shaft, disks supported upon said shaft and constituting the outer side walls of the auxiliary hoppers, and the dropping-tubes, pickers and doffers associated with said disks, 80 a spring-actuated rock-shaft mounted upon the rear side of the hopper, and having arms extending through the rear wall of said hopper, agitators upon said arms, and means for transmitting motion from the revolute shaft 85 to said rock-shaft.

6. In a potato-planter, the combination of revolute disks associated with and constituting the outer walls of hoppers and dropping-tubes, said disks being spaced from the 90 flanges constituting the end walls of said hoppers and tubes, pickers disposed upon the inner sides of said disks, and approximately parallel to the edges thereof, doffing-levers pivotally connected with the disks and having raised ends engaging the under sides of the pickers, counterweights at the opposite ends of said doffing-levers, and studs to limit the motion of the latter under the impulse of the counterweights.

7. In a device of the class described, the combination of a planter-frame, a base mounted upon the latter, uprights at the ends of said base, a shaft mounted in said uprights, a tube revolute upon said shaft, a main hopper supported upon the base, auxiliary hoppers associated with said main hopper, dropping-tubes connected with said auxiliary hoppers, disks secured upon the revolute tubular shaft and constituting the outer walls 105 of the auxiliary hoppers and the dropping-tubes, pickers and doffers associated with said pickers, trip-bars secured to the main hopper and extending across the dropping-tubes, and chutes leading from the latter to 110 the runners of the planter-frame.

In testimony that I claim the foregoing as my own I have hereto affixed my signature in the presence of two witnesses.

GEORGE HARVEY ELMER.
